DRIVE-PEG TOY

Olai F. Larsen, Jr., Demarest, N. J., assignor to
 Noma Electric Corporation, New York, N. Y.,
 a corporation of New York

Application April 12, 1945, Serial No. 587,863

11 Claims. (Cl. 46—1)

1

This invention relates to reversible drive-peg toys, i. e., toys having a plurality of pegs tightly fitted in through apertures in a board, the pegs being longer than the board is thick, whereby they project from a top or bottom surface of the board, and a projecting end of a peg may be pounded with a hammer to drive the peg part way through the board and cause the other end of the peg to project from the opposite face of the board.

It is an object of the invention to provide a reversible drive-peg toy wherein the pegs are so disposed that they may be driven naturally by a young child.

A further object of the invention is to provide an easily reversible drive-peg toy in which the surfaces of the peg carrying board are unclogged with supporting elements, so that a child can hammer the pegs without fear of striking anything except a peg.

An additional object of the invention is to provide a drive-peg toy in which the peg carrying board may be reversed simply, yet without having to turn the entire toy upside down.

Other objects of the invention will in part be obvious and in part hereinafter pointed out.

The invention accordingly consists in the features of construction, combinations of elements, and arrangement of parts which will be exemplified in the constructions hereinafter described, and of which the scope of application will be indicated in the appended claims.

In the accompanying drawings in which are shown various possible embodiments of this invention,

Fig. 1 is a top plan view of a reversible drive-peg toy embodying my invention;

Fig. 2 is a sectional view therethrough, taken substantially along the line 2—2 of Fig. 1; and

Fig. 3 is a sectional view through the toy taken substantially along the line 3—3 of Fig. 2.

At the present time commercial reversible drive-peg toys comprise a squat, H-shaped frame of which the crossbar of the H is a flat board in which a plurality of pegs is tightly received in holes through which the same may be driven by pounding the pegs with a hammer. The uprights of the H function as supports to prevent the pegs from striking the floor when they are driven. These uprights extend to both sides of the crossbar, inasmuch as the toy must be capable of being turned upside down to expose the pegs projecting from the lower surface of the crossbar so that they too can be driven.

Such construction has several drawbacks. In

the first place, the uprights clog the surface of the board from which pegs project, so that a child trying to strike a peg, instead is likely to strike an upright. Secondly, the entire toy must be turned upside down to ready the rather heavy toy for further use after the projecting ends of the pegs have been driven flush with the upper surface of the board.

It has been proposed to overcome these drawbacks by providing a peg carrying board which is slidably received in the open end of a box by tongue and groove joints. This, however, entailed too difficult a reversing operation for a child as young as one for whose use the toy is intended.

In addition, I have observed that young children have considerable difficulty in driving the pegs. This I have determined is due to the fact that small children are unable to naturally handle a hammer in such manner as to bring its driving face down flat against the top of a peg.

Pursuant to my invention, I avoid all these drawbacks by providing a drive-peg toy whose peg carrying board is pivotally mounted at one end thereof, whereby said board may be swung over easily to expose either face from which pegs project. The support for the opposite end of the board is so arranged that said end is always lower than the pivotally mounted end, thereby inclining the surface of the board and causing the axes of the pegs to be likewise inclined so that a child can drive the pegs more naturally. Since only the peg carrying board, and not the entire toy, is reversed the supporting elements need not extend above the upper surface of the board in either of its positions.

Referring now to the drawings, and, more particularly, to Figs. 1—3, 10 denotes a reversible drive-peg toy embodying my invention. Said toy comprises a rectangular frame consisting of two wooden side boards 12, 14 and two wooden end boards 16, 18 held in assembled relationship by any suitable connecting means, not shown, such as glue, jointing, screws, nuts and bolts or pins.

The peg carrying element comprises a flat wooden board 20 having a plurality of normal apertures 22 running from the upper face 24 to the lower face 26 of the board. Pegs 28 received in the apertures have their longitudinal axes perpendicular to the board. The pegs are of such size that they snugly fit in the apertures. If desired, said pegs may have diametrical kerfs 30 cut in both ends thereof, the kerfs at the two ends of each peg being at right angles and overlapping each other so that the pegs are resiliently constrictable over their entire length.

One end 32 of the peg carrying board 20 is rotatably mounted on the frame of the toy. Any suitable means may be employed to effect such mounting. By way of example, I have shown said end of the board provided with an elongated bore 34 in which a pivot pin 36 is received. Said pin is snugly fitted in apertures 37 in the side boards 12, 14 and the ends of the pin are headed to prevent the pin from being axially displaced.

The opposite end 38 of the board 20 rests on the top edge of one or the other end boards 16, 18. Thus it will be seen that the peg carrying board may be swung easily from a position in which it rests on one of said end boards, to a position in which it rests on the other of said end boards. This constitutes the construction which enables my toy to have the peg carrying board reversed simply and easily, without the necessity of turning the entire toy.

In Fig. 2 the solid line showing of the peg carrying board 20 illustrates the position of said board and pegs when all of the pegs have had their upper ends driven in flush with the top of the board. The dot-and-dash line showing of the peg carrying board in the same figure indicates the position of said board and peg after the board has been turned about the pivot pin 36. It will be observed that the projecting ends of the pegs which, when on the right hand side of the toy were concealed, are now exposed and ready for the child to hammer down again into the board.

To present a pleasing appearance to the toy, I prefer to locate the pivot pin 36 approximately midway between the two end boards 16, 18.

It will be appreciated that the frame need not be inverted to support the peg carrying board 20 above the floor in either of the reversed positions of the board. The two upper edges of the side boards preferably are so designed as to be flush with the top surface of the peg carrying board and in no event to extend substantially above said surface, thereby avoiding the presence of any encumbrance on the operative surface of the board and yet not so complicating the manipulation of the toy that a young child can no longer handle the same.

If desired, the central portion of the top edges of the end boards 16, 18 may have indentations 40 formed therein to facilitate turning of the board 20 and to lessen the likelihood of a child's hand being struck when the board is turned.

To incline the operative surface of the peg carrying board 20 I may so dispose the pin 36 with regard to the top edges of the end boards 16, 18 that the rotatably mounted end 32 of said board will be disposed either below or above the free end 38 of said board which rests upon one or the other of such top edges. I prefer to have the pin so arranged that the rotatably mounted end 32 of the board is higher than the free end 38 thereof, as this enables a child to sit right next to the board while the same slopes down toward him. Desirably the top edges of the two end boards 16, 18 are substantially the same height, so that in either position the board will slope at approximately the same angle. It will be understood, however, that this is not necessarily to be construed as a limitation upon the invention.

I have found that when the board is inclined at about an angle of 10° to the floor a child can drive pegs very naturally. However, driving of the pegs by a tot is greatly facilitated by tilting the board from as little as 5° to as much as 45°.

It will thus be seen that I have provided toys which achieve the several objects of the invention and are well adapted to meet the conditions of practical use.

As various possible embodiments may be made of the foregoing invention, and as various changes might be made in embodiments above set forth, it is to be understood that all matter herein described, or shown in the accompanying drawings is to be interpreted as illustrative and not in a limiting sense.

Having thus described my invention, I claim as new and desire to secure by Letters Patent:

1. A drive-peg toy comprising a peg carrying board, a plurality of pegs tightly fitted in through apertures in said board, said pegs being longer than the board is thick and disposed with their longitudinal axes perpendicular to the top and bottom of the board, and means to reversibly support said board at a sufficient distance from the floor to permit the pegs to be driven into the board and project from the lower surface thereof, said supporting means comprising a frame and a mechanism to rotatably mount one end of said board on said frame.

2. A drive-peg toy comprising a peg carrying board, a plurality of pegs tightly fitted in through apertures in said board, said pegs being longer than the board is thick and disposed with their longitudinal axes perpendicular to the top and bottom of the board, and means to reversibly support said board at a sufficient distance from the floor to permit the pegs to be driven into the board and project from the lower surface thereof, said supporting means comprising a frame and a mechanism to rotatably mount one end of said board on said frame, the free end of said board resting upon either one of two elements of said frame on opposite sides of said mechanism.

3. A drive-peg toy comprising a peg carrying board, a plurality of pegs tightly fitted in through apertures in said board, said pegs being longer than the board is thick and disposed with their longitudinal axes perpendicular to the top and bottom of the board, and means to reversibly support said board at a sufficient distance from the floor to permit the pegs to be driven into the board and project from the lower surface thereof, said supporting means comprising a frame and a mechanism to rotatably mount one end of said board on said frame, the free end of said board resting upon one of two elements of said frame on opposite sides of said mechanism, the axis of rotation of said rotatable mounting mechanism being disposed out of the horizontal plane extending through at least one of said elements to an extent sufficient to incline the board when resting on said one element.

4. A drive-peg toy comprising a peg carrying board, a plurality of pegs tightly fitted in through apertures in said board, said pegs being longer than the board is thick and disposed with their longitudinal axes perpendicular to the top and bottom of the board, and means to reversibly support said board at a sufficient distance from the floor to permit the pegs to be driven into the board and project from the lower surface thereof, said supporting means comprising a frame and mechanism to rotatably mount one end of said board on said frame, the free end of said board resting upon one of two elements of said frame on opposite sides of said mechanism, the axis of rotation of said rotatable mounting mechanism being disposed above the horizontal plane extending through at least one of said elements to

an extent sufficient to slope the board down from said mechanism when resting on said one element.

5. A drive-peg toy comprising a four-sided frame, including two sides and two ends, the center of said sides being higher than the ends thereof, a peg carrying board, a plurality of pegs tightly fitted in through apertures in said board, said pegs being longer than the board is thick and disposed with their longitudinal axes perpendicular to the top and bottom of the board, and means to rotatably mount an end of said peg carrying board at the center of the sides, with the axis of rotation thereof above the top edges of the ends, the free end of said peg carrying board being adapted to rest upon one or the other of the top edges of said ends whereby said peg board in either such position is disposed at an angle to the floor.

6. A drive-peg toy comprising a four-sided frame, including two sides and two ends, the center of said side being higher than the ends thereof, a peg carrying board, a plurality of pegs tightly fitted in through apertures in said board, said pegs being longer than the board is thick and disposed with their longitudinal axes perpendicular to the top and bottom of the board, and means to rotatably mount an end of said peg carrying board at the center of said sides, with the axis of rotation thereof above the top edges of the ends, the free end of said peg carrying board being adapted to rest upon one or the other of the top edges of said ends whereby said peg board in either such position is disposed at an angle to the floor, said top edges having an indentation therein to facilitate turning of the peg carrying board about said rotatable mounting means.

7. A drive-peg toy comprising a four-sided frame, including two sides and two ends, the center of said sides being higher than the ends thereof, a peg carrying board, a plurality of pegs tightly fitted in through apertures in said board, said pegs being longer than the board is thick and disposed with their longitudinal axes perpendicular to the top and bottom of the board, means to rotatably mount an end of said peg carrying board at the center of the sides, with the axis of rotation thereof above the top edges of the ends, the free end of said peg carrying board being adapted to rest upon one or the other of the top edges of said ends whereby said peg board in either such position is disposed at an angle to the floor, the top edges of said sides being so arranged and of such configuration that the same do not project substantially above the top surface of the peg carrying board in either position thereof.

8. A drive-peg toy comprising a frame, including two sides and two ends, a peg carrying board, a plurality of pegs tightly fitted in through apertures in said board, said pegs being longer than the board is thick and disposed with their longitudinal axes perpendicular to the top and bottom of the board, said peg carrying board being freely received between the two sides and having an end thereof resting upon one or the other of the top edges of said ends, and means to rotatably mount the other end of said peg carrying board between said sides whereby said board may be turned from a position in which one of its free ends rests upon the top edge of one of said ends to a position in which said free end rests upon the top edge of the other end.

9. A drive-peg toy comprising a frame, including two sides and two ends, a peg carrying board, a plurality of pegs tightly fitted in through apertures in said board, said pegs being longer than the board is thick and disposed with their longitudinal axes perpendicular to the top and bottom of the board, said peg carrying board being freely received between the two sides and having an end thereof resting upon one or the other of the top edges of said ends, and means to rotatably mount the other end of said peg carrying board between said sides whereby said board may be turned from a position in which one of its free ends rests upon the top edge of one of said ends to a position in which said free end rests upon the top edge of the other end, said rotatable mounting means being disposed substantially above the top edges of said ends, so that in either position said peg carrying board is disposed at an angle to the floor.

10. A drive-peg toy comprising a frame, including two sides and two ends, a peg carrying board, a plurality of pegs tightly fitted in through apertures in said board, said pegs being longer than the board is thick and disposed with their longitudinal axes perpendicular to the top and bottom of the board, said peg carrying board being freely received between the two sides and having an end thereof resting upon one or the other of the top edges of said ends, and means to rotatably mount the other end of said peg carrying board between said sides whereby said board may be turned from a position in which one of its free ends rests upon the top edge of one of said ends to a position in which said free end rests upon the top edge of the other end, said rotatable mounting means being disposed substantially above the top edges of said ends, so that in either position said peg carrying board is disposed at an angle to the floor of from between 5° and 45°.

11. A drive-peg toy comprising a frame, including two sides and two ends, a peg carrying board, a plurality of pegs tightly fitted in through apertures in said board, said pegs being longer than the board is thick and disposed with their longitudinal axes perpendicular to the top and bottom of the board, said peg carrying board being freely received between the two sides and having an end thereof resting upon one or the other of the top edges of said ends, and means to rotatably mount the other end of said peg carrying board between said sides whereby said board may be turned from a position in which one of its free ends rests upon the top edge of one of said ends to a position in which said free end rests upon the top edge of the other end, said rotatable mounting means being disposed substantially above the top edges of said ends, so that in either position said peg carrying board is disposed at an angle to the floor of about 10°.
